United States Patent Office

Des. 195,664
Patented July 16, 1963

195,664

DISPENSER

John B. Wilson, Chesterfield County, Va., assignor to Reynolds Metals Company, Richmond, Va., a corporation of Delaware

Filed Oct. 13, 1960, Ser. No. 62,471

Term of patent 14 years

(Cl. D2—3)

FIG-1

FIG-2.

FIG. 1 is a front perspective view of a dispenser, showing my new design.

FIG. 2 is a side elevational view thereof.

FIG. 3 is a rear perspective view of the dispenser of FIG. 1.

FIG. 4 is an enlarged, fragmentary, axial cross-sectional view of the dispenser of FIG. 1.

The dominant features of my design are shown in full lines.

I claim:

The ornamental design for a dispenser as shown and described.
